(57) **CLAIM**

The ornamental design for automobile exterior trim, as shown and described.

DESCRIPTION

FIG. 1 is a front perspective view of the front, top and right side of an automobile showing my new design;

FIG. 2 is a rear perspective view of the rear, top and right side thereof;

FIG. 3 is a right side view thereof;

FIG. 4 is a left side view thereof;

FIG. 5 is a front view thereof;

FIG. 6 is a rear view thereof; and,

FIG. 7 is a top plan view thereof.

The broken lines showing the automobile are for the purpose of illustrating environmental structure and form no part of the claimed design.
